(57) **CLAIM**

The ornamental design for an side-by-side vehicle as shown and described.

DESCRIPTION

FIG. 1 is a front elevation view of a side-by-side vehicle embodying my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top-front-right side elevation view thereof; and,

FIG. 8 is a top-rear-left side elevation view thereof.

The light-grayed-out portions showing of the all-terrain vehicle are provided for the purpose of illustrating environmental structure and do not form part of the claimed design.

1 Claim, 8 Drawing Sheets
